[57] CLAIM

The ornamental design for a bush cutter, as shown and described.

DESCRIPTION

FIG. 1 is a top, front and side perspective view of a bush cutter showing our new design;

FIG. 2 is a top, rear and side perspective view thereof;

FIG. 3 is a side elevational view thereof;

FIG. 4 is a bottom plan view thereof;

FIG. 5 is a rear elevational view thereof;

FIG. 6 is a front elevational view thereof;

FIG. 7 is a side elevational view of the opposite side of FIG. 3;

FIG. 8 is a top plan view thereof; and

FIG. 9 is a top, front and side perspective view of a second embodiment thereof, the only difference residing in the handles.

FIG. 1

FIG. 2

FIG. 3

FIG. 4

FIG. 5

FIG. 6

FIG. 9
